UNITED STATES PATENT OFFICE.

WILLIAM O. KLEINE, OF CINCINNATI, OHIO.

GLOBE HOLDER FOR ELECTRIC AND GAS LIGHT FIXTURES.

Application filed January 24, 1922. Serial No. 531,484.

The object of my invention is to provide a means for securing globes in place on electric and gas lamp standards and interior lighting fixtures of various kinds, in which 5 the globe can be readily and easily secured or removed without the use of holding screws in a minimum space of time, with a globe holder involving a minimum number of parts and in which the globe shall be held 10 under spring tension practically suspended between resilient points of support, whereby the breakage incident to sudden jars or vibrations shall be reduced to a minimum, and a liability of fracture of the globe, due 15 to unequal expansion and contraction of the globe and holder, which would be the case when held by screws adjusted too tightly, is obviated.

While my holder is adapted for use in 20 exterior and interior illumination and for all sorts of gas and electric light fixtures, whether upright, pendant or of bracket construction, I have illustrated a construction especially arranged for the securing of 25 globes in position for electric or gas street lighting upright standards.

The invention consists of that certain 30 novel construction and arrangement of parts to be hereinafter particularly pointed out and claimed, by which the above results are obtained.

In the drawings,

Figure 1 is a central vertical section of my holder with a globe in position thereon.

35 Figure 2 is a top plan view, partly broken away, with the globe removed and the clamps in locked position.

Figure 3 is a plan of the sub-base, or fixed 40 supporting plate, by which the holder is secured to the post or standard.

Figure 4 is a section of the sub-base.

Figure 5 is a perspective view of the 45 spring clamp plate and eccentric or cam piece for operating the same.

Figure 6 is a plan view and Figure 7 is a section of the base plate for holding the globe.

Figure 8 is a plan view of the holder with globe removed and the clamps in releasing 50 position.

Figure 9 is a side elevation of the upper portion of the lamp post with the holder in place and showing automatic locking device.

55 As shown in the drawings, I have selected

for illustration a particular construction designed for boulevard street lighting posts, and for mounting the holder I provide an annular plate or sub-base 1, open in the center and with a bridge piece 2, which, in the present instance, is depressed to bring the electric light source to the proper height with relation to the globe and which is provided with depending flanges 3 for securing therein an electric lamp socket. The bridge 60 piece may, of course, be flat or raised, and any other convenient method may be employed for mounting and securing the type of lamp socket selected.

The sub-base 1 is secured to the head of 70 the light standard or post head 4 by screws or bolts through the holes 5.

Mounted on top of the sub-base and adapted to oscillate thereon is the annular base plate 6 with a peripheral upturned flange 7. 75 The outer portion of the base plate 6 is depressed at 8 and the sub-base plate 1 is offset at 9 so as to allow an annular space 10 for clearance of bolt heads and other devices mounted on the base.

80 The base plate 6 is provided with a plurality of arcuate slots 12 for the reception of studs, supporting cam pieces and clamp plates employed, and, as illustrated, I have provided for three of such studs, cam pieces 85 and clamp plates, set 120 degrees apart, which I found sufficient, although the number may be more or less. Mounted in these slots are the projecting studs 13 secured to the sub-base plate 1, through the openings 15^a by nuts or in any other suitable way.

85 The studs 13 each carry a U-shaped piece 15 mounted to oscillate around the stud which passes through openings in the open end of the U-shaped piece. The base 6 is 90 also provided with short radial slots 16 corresponding in number to the slots 12 and the U-shaped pieces each have a dog 17 or downwardly projecting arc which engages in its respective radial slots 16. Secured by 95 rivets or otherwise to the flat upper portion of each U-shaped piece is a resilient plate 18 curved slightly upwardly at its free end, and these plates serve as the clamp plates for the globe and turn freely around the 100 studs 13.

105 The base plate 6 is provided with outwardly projecting ears 19 which serve as handles to facilitate turning the base plate. The effect of this turning will change the 110

position of the studs 13 from one end to the other of the slots 12 and the retention of the U-shaped pieces 15 by the dogs 17 will cause the U-shaped pieces and the clamp plates to 5 turn from the position shown in Figure 8 to that shown in Figure 2 or vice versa, the U-shaped pieces acting as cams, and the lengths of the slots 12 are such as to limit the travel and to prevent the clamp plates 10 from coming in contact with the lamp socket when turned in and to extend the clamps out radially when turned in the other direction.

Riveted or otherwise secured to the base 6 and preferably intermediate the clamp plate 15 mountings are flat plates 20 of resilient material which serve as seats for the globe. These plates and also the clamp plates are 20 preferably constructed of phosphor bronze, because of its heat resisting and rust-proof qualities, and the flat plates have freedom of movement in the depressed portion 8 of the base.

With the clamp plates 18 turned as shown in Figure 8, the globe 21 is seated on the 25 resilient plates 20 within the flange of the base and the base is then turned to throw the clamps outwardly, which brings the outer edges of the clamps to bear on the inside of the ridge of the globe, holding the globe down on the resilient seat plates 20.

In order to lock the base plate 6, the ears 19, which are riveted to the flanges of the base plate 6 by an angle plate 23, are formed with a depending portion 22 which engages 35 in the slots 24 in an extension 25 from the sub-base 1.

In order to adjust and to regulate the tension of the clamp plates 18, each plate is 40 provided with a set screw having an upset head 26 and screwed into the cam piece 15.

The operation of the holder is exceedingly 45 simple. To secure it in place on the standard or post, the base plate 6 is provided with holes 27 which are in such position so as to make accessible the attaching screws, which 50 are passed through the holes 5 in the sub-base. The base is turned so as to unlock the clamps, and the globe is inserted in position and the base plate turned, forcing the 55 clamps to slide over and on top of the inside ridge of the globe securely holding it in position.

The clamps and the seat plates being of 55 resilient metal, the globe is practically held in suspension between the two springs and this also automatically takes care of expansion and contraction. The clamp and seat plates act as a cushion both vertically and laterally.

The glass globe will therefore be protected 60 against breakage due to any sudden jar or impact, as well as breakage due to general vibration, which in the case of ordinary holders, where the glass globe rests directly 65 on the cast iron base, causes a chipping of

the globe at the base, or total breakage due to the glass coming into contact with the iron sides.

There being a complete absence of screws to hold the globe in place, it is impossible to 70 break the globe by forcing screws in too far against the glass and not allowing for expansion and contraction, as is the case with ordinary holders.

It is also a great time and labor saving 75 device, obviating as it does the necessity for securing the globe with screws; the simple movement of the base plate a distance of slightly more than one inch instantaneously 80 either locking in position or opening the holder.

The peripheral depression in the base plate, in addition to providing space for the resilient movement of the seat plates, also 85 serves as a water shed or gutter preventing water from running down inside of the standard or post and openings 29 are provided to discharge any water collecting in the gutter.

Having thus described my invention, what 90 I claim as new and which I desire to secure by Letters Patent, is:—

1. In a device of the character described, the combination with a fixed supporting plate and a base plate mounted to rotate thereon, of rotatable clamp plates, cam pieces upon which the clamp plates are mounted and secured to one plate and in engagement with the other, whereby the movement of the base plate will cause the 100 clamp plates to engage the globe resiliently, securely holding the latter in position, and resilient members secured to the base plate upon which the globe may rest.

2. In a device of the character described, the combination with a fixed supporting plate and a base plate mounted to rotate thereon, studs mounted on the fixed supporting plate and projecting through slots in the base plate, a cam member mounted on 110 each stud, with connection for the cam member with the base plate, and a resilient clamp plate carried by the cam member, whereby the rotation of the base plate causes the cam member to rotate and to throw the clamp member in and out of operation.

3. In a device of the character described, the combination with a fixed supporting plate and a base plate mounted to rotate thereon, studs mounted on the fixed supporting plate and projecting through slots in the base plate, a cam member mounted on each stud, with connection for the cam member with the base plate, and a resilient clamp plate carried by the cam member, with 120 means for adjusting the tension of the clamp plate, whereby the rotation of the base plate causes the cam member to rotate and to throw the clamp member in and out of 125 operation.

4. In a device of the character described, the combination with a fixed supporting plate and a base plate mounted to rotate thereon, with resilient members secured to the base plate upon which the globe may rest, studs mounted on the fixed supporting plate and projecting through slots in the base plate, a cam member mounted on each stud, with connection for the cam member with the base plate, and a resilient clamp plate carried by the cam member, whereby the rotation of the base plate causes the cam

member to rotate and to throw the clamp member in and out of operation.

5. In a device of the character described, a relatively fixed plate, with resilient supports thereon for a light shade, a plate mounted to oscillate on the relatively fixed plate, shade holders to engage the shade from the inside, and mechanism intermediate the two plates whereby the movement of the oscillating plate will oscillate the shade holders to engage the shade from the inside. 20

WILLIAM O. KLEINE.
